POWER TRANSMITTING MECHANISM

Edward Snyder, Fort Wayne, Ind., assignor to
General Cable Corporation, New York, N. Y., a
corporation of New Jersey

Application June 13, 1930, Serial No. 460,805

5 Claims. (Cl. 192—58)

This invention relates to power transmitting mechanism which may be used, for example, for winding a continuous strand of material such as a wire upon a spool. It is an object of this invention to provide improved power transmitting mechanism suitable for spooling a strand with substantially uniform tension. Other objects and advantages of the invention will appear hereinafter.

0 A preferred illustrative embodiment of the invention is shown in the accompanying drawings, in which:—

Fig. 1 is a plan view of a spooling mechanism, portions being broken away to disclose the construction;

5 Fig. 2 is an end view of the cellular driving head of the spooler; and

Fig. 3 is an end view of the head of the driven member of the spooler.

10 In spooling strand material it often is desired to wind the strand under substantially uniform tension, and to maintain a substantially constant linear winding speed for the strand. When the strand is wound on the spool in superposed layers, and forms thereon a coil of increasing diameter, the increased winding diameter must be compensated for by a variation in the speed of the spool if the linear speed of the strand is to remain uniform, and by a variation in the torque applied to the spool if the tension on the strand is to remain uniform. Desirably, apparatus of this nature will be operable at different speeds and adjustable as to tension to accommodate strands of different size

15 or strength.

Apparatus of this character is desirable, for example, in wire drawing machines. In the usual practice in wire drawing machines the wire is drawn through a series of dies by power driven capstans and is wound in overlying layers on a power driven spool. The rate of travel of the wire through the machine is dependent upon the tension applied to the wire as it passes around the capstans and to the spool. If the tension exerted on the wire by the spool can be kept constant at the optimum value which causes the wire to be drawn through the machine at the most efficient speed and with a minimum of slippage on the capstans, the output of the machine will be uniform at or near its maximum value without impairing the wire because of excessive friction or slippage between the wire and capstans, and without stretching or breaking the wire.

20 Referring to the drawings, the spooling mech-

anism illustrated in Figs. 1, 2 and 3 has a revolving spool 6 upon which the wire is to be wound. The spooling mechanism has a pair of aligned bearings 8 and 9 spaced apart and conveniently supported as upon a base 10. In the bearing 8 is supported a driving member consisting of a tubular drive-shaft 11 provided at its outer end with a sheave 12 secured thereon which is actuated by a belt 13 whereby rotary motion in the bearing is imparted to the driving member. Upon the inner end of the shaft 11 is secured a cellular head preferably consisting of a disc 14 disposed concentrically with respect to said shaft and having contiguous with its outer perimeter extending axially from its rear face 15 an annular flange 15, and also a series of radially disposed blades 16 equally spaced, each of which extends axially from the disc 14 to the opposite edge of the flange 15. Thus, there is provided in the head an annular series of cells 17 separated by said blades, closed at their rear ends by the flange 14 and open at the forward end of the head.

25 The disc 14, if so desired, may have made in its inner face one or more concentric annular recesses 14' (Figs. 1 and 2) whereby passageways are provided between the blades 16 and the disc 14 to permit air to circulate therethrough between the cells 17 of the cellular head. Also, the tubular drive-shaft is provided at its outer end with a removable stopper 11' by which the bore 11" of the drive-shaft is closed.

30 In the bearing 9 is supported a driven member consisting of a spool shaft 18 rotatably mounted in said bearing and having removably mounted axially upon its outer end a spool 6. Upon the inner end of said shaft 18 is secured a cylindrical head preferably consisting of a disc 20 having an annular flange 21 extending axially from the periphery thereof, and a series of radially disposed blades 22, each of which extends axially from the disc 20 to the plane of the opposite edge of the flange 21. The outer ends of the blades 22 preferably terminate at points spaced from the flange 21 so there are provided corresponding air passageways 21' between said blades and said flange.

35 The cellular head of the driving member and the cylindrical head of the driven member are oppositely disposed, axially aligned and spaced apart in close proximity to each other so that the open end of the cellular head is exposed to the open end of the head of the driven member. Upon rotation of the driving member fluid, such as the air surrounding the cellular head, is

set in motion, and thereby the cylindrical head of the driven member is impelled yieldingly in the same direction of rotation as the driving member.

5 The force with which the driven member is actuated by the cellular head through the medium of fluid moved thereby will be lessened to an extent because of the passageways provided by the annular recesses 14' which permit circulation of fluid between the cells 17 as the cellular head revolves. By removal of the stopper 11' fluid may be admitted through the bore 11'' of the drive-shaft 11 into the cellular head whereby the force with which the driven member is actuated is further reduced. In some instances, especially when spooling very fine wire, it is desirable that the force applied to the driven member is such as will permit the driven member to lag when the tension applied to the wire occasioned by the rotation of the spool reaches or approaches the maximum permissible value.

It will be understood that the provision of the passageways between the blades 16 and the disc 14 to permit circulation of fluid between the cells 17, and also the provision for the admission of fluid through the drive-shaft into the cellular head, are refinements that contribute facility by which delicacy in the operation of imparting movement from the driving member to the driven member is attained. The passageways 21' between the flange 21 on the head of the driven member and the outer ends of the blades 22 thereof permit circulation of fluid from the spaces in said head between the blades, which diminishes the effectiveness of the force that imparts movement to the driven member. This also is a refinement whereby the effect of the moving fluid upon the driven member through the action of the driving member is modified, which is beneficial especially in winding wire of fine grades. However, in some instances, the admission of fluid through the bore of the drive-shaft, the provision of the recesses 14' to permit the circulation of fluid between the cells, and the provision of passageways 21' in the driven member, or any of them, may be dispensed with, although it is desirable that one or more of them be incorporated in the structure as need thereof is occasioned.

50 By means of the belt 13 and sheave 12, the driving member is rotated at substantially constant speed. The driven member upon which the spool 6 is mounted is rotatably impelled by the fluid set in motion by the driving member causing the wire to become wound upon the spool and a pull to be exerted upon the wire to an extent limited by the torque imparted to the driven member. The wire thus becomes correspondingly tightened about the capstans 55 and is drawn by the spool from the wire drawing apparatus at a rate of progress limited in extent by the velocity of the capstans and dependent upon the pull of the wire occasioned by the torque of the spool.

60 The torque exerted upon the driven member through the medium of the fluid by the driving member is dependent upon the speed with which the driving member rotates. By suitably altering the belt drive for the driving member so that the speed of the driving member is increased, the torque imparted to the driven member and the pull exerted upon the wire by the spool are proportionately accentuated, and vice versa. Also, the torque imparted to the driven member and the pull exerted upon the wire

by the spool may be softened by enlarging the passageways between the cells 17 of the cellular head, or the passageways 21' in the head of the driven member, or by the admission of fluid through the bore of the shaft 11 of the driving member, as is occasioned upon removal of the stopper 11' from the end of said drive-shaft.

5 A salient feature of the invention is the manner in which movement is yieldingly imparted from the driving member, to the driven member by which the spool is actuated, and whereby the speed of the driven member is automatically lessened as the coil of wire accumulating upon the spool increases in diameter. Through the instrumentality of fluid set in motion by the cellular head and applied to the head of the driven member while substantially confined within and between said heads, a variable torque driving connection is established between the driving and driven members whereby the torque of the spool is increased as its speed is restrained because of enlargement of the wire coil thereon, and thus the pull of the wire is sustained under substantially uniform tension throughout the winding operation.

25 While the invention has been illustrated and described with reference to certain physical embodiments, it will be understood that the invention is susceptible of various modifications and embodiments and is to be limited only by the 30 claims.

I claim:

1. In apparatus of the class described, a base having spaced bearings; a rotatable drive-shaft in one of said bearings having means for actuating it; a rotatable driven shaft in the other of said bearings; a head on said drive-shaft closed at one end and open at its other end and having an annular series of cells therein, there being fluid passageways in said head affording communication between said cells; and a cylindrical head on said driven shaft having radially disposed blades exposed to the open end of the head on said drive-shaft whereby said driven shaft is actuated by fluid set in motion and imparted to said blades by the head on said drive-shaft.

2. In apparatus of the class described, a driving member rotatably mounted including means for actuating it; and a driven member rotatably mounted adjacent one end of said driving member, said driving member being provided with a cup-shaped head having an annular series of cells therein that are exposed through one end of said head, said driven member having a cylindrical head closed at one end, its opposite end being open and exposed to the open ends of said cells and having a series of radially disposed blades therein that terminate at their outer ends at points spaced from the outer wall thereof to provide air passageways therebetween.

3. In apparatus of the class described, a driving member rotatably mounted including means for actuating it; and a driven member rotatably mounted adjacent said driving member, said driving member being closed at one end and open at its opposite end and having an annular series of cells that are exposed through the open end of said head, there being provided air passageways connecting said cells at their inner ends, said driven member having a cylindrical head closed at one end, its opposite end being open and exposed to the open ends of said cells and having a series of radially disposed blades therein.

4. The combination in a power transmitting

mechanism of alined, independently rotatable driving and driven shafts, a cup-shaped head secured on the inner end of said driving shaft, said head having a series of radially disposed blades therein, a second cup-shaped head secured on the inner end of said driven shaft, this second head also having a series of radially disposed blades therein, the two heads being mounted on the adjacent ends of the alined shafts with their open ends opposed in closely spaced relation with each other but otherwise open to the atmosphere, so that air set in motion by the head on the driving shaft yieldingly imparts rotary movement of the head on the driven shaft.

5. The combination in a power transmitting mechanism of alined, independently rotatable driving and driven shafts, a cup-shaped head secured on the inner end of said driving shaft, a series of radially disposed blades in said head forming an annular series of cells, a passageway between said cells adjacent the inner ends of the radially disposed blades, a second cup-shaped head secured on the inner end of said driven shaft, a series of radially disposed blades in this second head forming an annular series of cells, a passageway between the last mentioned cells adjacent the inner ends of the radially disposed blades, the two heads being mounted on the adjacent ends of the alined shafts with their open ends opposed in closely spaced relation with each other, so that fluid set in motion by the head on the driving shaft yieldingly imparts rotary movement to the head on the driven shaft.

5. The combination in a power transmitting mechanism of alined, independently rotatable driving and driven shafts, a cup-shaped head
